UNITED STATES PATENT OFFICE

FRANCOIS R. MARCEL, OF BROOKLYN, NEW YORK

CURLING IRON

Application filed March 20, 1931. Serial No. 523,983.

My invention relates to curling irons and it embodies several different features which are capable of use independently of each other but which, when combined, co-operate to provide a most efficient curling iron. The subject of the invention may be employed in a curling iron which is to be gas heated or it may be embodied in an iron adapted to be heated by an electric resistance heater arranged within one of the members of the iron, the invention in no way affecting the method by which the iron is heated.

One of the desirable objects to be obtained with a curling iron is to tightly grip the lock of hair between the spoon member and the rod member in a manner which will permit pressure to be applied to the hair. In the waving of hair heat is only one factor to be considered because in addition it is necessary to obtain proper pressure and tension as otherwise the mere application of heat will result in only a temporary wave; i. e., a wave which will disappear from the hair in a few hours. But where the pressure and heat are both effectively applied the hair will remain waved over longer periods.

In the present case I have provided a curling iron in which the rod and spoon co-operate to snugly grip the hair along one edge of the spoon and then by a rocking motion of the rod member crowd the hair in such manner as to more effectively wave it than is possible with the irons heretofore made.

This is made possible insofar as the movement of the rod in relation to the spoon member is concerned, by having a single pivot connecting the spoon member and rod member so that the rod member may rock as well as pivot and the pressure as the rod approaches the spoon will be primarily toward one edge of the spoon.

Another object of my invention is to provide means of adjustment for controlling the closed position of the spoon and rod members in such manner that the hair may be gripped tightest near the pivotal connection of these members or near the outer ends. This adjustable feature determines the relative angle of the rod and spoon members

when they are in closed position. Heretofore, curling irons have been made with a fixed relation between the rod and spoon members, no adjustment being provided to permit the user to adjust the iron to suit his or her particular taste or method of use. With the present device the user may, by adjusting the stop screw, cause the spoon and rod members to lie closer together near their outer ends or to lie closer together toward the pivotal point, or these members may be adjusted to lie parallel with each other.

Some hairdressers prefer to engage the lock of hair nearer the point of the iron than the pivot and the present iron is adjustable to suit the taste or the whims of the operator. In every case it is desirable that the proper pressure may be applied to the lock of hair wherever the same engages in the iron and this is made possible with the present device.

Another object of my invention is to provide a flange on the rod member projecting over and engaging one of the longitudinal edges of the spoon member for the purpose of applying heat and pressure to the hair where it bends over the edge of the spoon for the purpose of producing what is known as a marcel wave. This feature is in the present case combined with a rocking or tilting fulcrum above referred to, and when so combined it is more effective than in the irons heretofore made. In my U. S. Letters Patent No. 1,277,739 and dated Sept. 3, 1918 I showed and claimed a curling iron having broadly this flange feature and the novelty in the present case as far as this feature is concerned, resides principally in the combination with the rocking fulcrum feature above referred to.

Another object of my invention is to make it possible to adjust the rod member laterally in relation to the spoon member in order to vary the pressure against the hair on either side of the spoon member. This is done by adjusting the fulcrum screw and it permits the other features of my invention to be used in conjunction with this lateral adjustment feature. Other objects and advantages will be set forth in the following description of my invention.

In the drawings forming part of this application,

Figure 1 is a side elevation of a curling iron embodying my invention, in which view the hair clamping members are shown in closed position in full lines and in open position in dotted lines,

Figure 2 is a sectional view taken on the line 2—2 of Figure 1 and is substantially a 10 plan view of the iron with one of the handles cut away by the section line,

Figure 3 is a sectional view taken on the line 3—3 of Figure 1,

Figure 4 is a longitudinal, central sectional 15 view of a portion of the iron showing the effect of one of the adjustments referred to herein,

Figure 5 is a similar view showing another effect of one of the adjustments,

20 Figure 6 is a horizontal sectional view of a portion of the iron on an enlarged scale, showing the means for pivotally connecting the spoon and rod members,

Figure 7 is a similar view showing the effect 25 of adjusting the rod and spoon members laterally in relation to each other,

Figure 8 is a side elevation of my invention having incorporated therein the flange member referred to,

30 Figure 9 is a cross sectional view through the rod and spoon members showing the same as these members start to close upon each other,

Figure 10 is a similar view showing the relation of these members when they are pressed 35 toward each other and the rod member is caused to rock in relation to the spoon member,

Figure 11 is a cross sectional view of the 40 spoon member alone, and

Figure 12 is a cross sectional view of the rod member alone, illustrating the mounting within the rod member of the ordinary type of electric heater.

45 Figure 13 is a detail view illustrating the free end of the rod received within the spoon member.

I will first describe my invention as embodied in the form shown in Figures 1 to 5 inclusive, which is what might be called the plain iron. Figures 6 and 7 illustrate parts of the iron regardless of whether it is of the plain type shown in Figures 1 to 5 or the flange iron shown in Figures 8 to 12 inclusive.

50 In Figures 1 to 5 I have shown co-operating members adapted to grip the hair between them and consisting of the rod member 1 which is usually circular in cross section and provided with a pointed end 2. The other member consists of a spoon 3 having a hollow recess to receive a portion of the rod member therein and this is usually provided with a pointed end 4 to facilitate insertion into the hair. The rod member extends to the right beyond the pivotal point as shown at

5 and this end of the rod is provided with a handle 6 of heat insulating material. The spoon member is provided with a yoke 7 and from this extends a rod 8 on which is mounted a second handle member 9 also of heat insulating material. The operator grasps the two handles and manipulates them to operate the rod and spoon members for engaging the hair and curling it about these members.

The rod and spoon members are connected with each other in the present case pivotally and so that they may rock and for this purpose I have shown a screw 10 which extends through an aperture 11 in one side of the yoke 7 the aperture being slightly larger than the 70 diameter of the screw to give a certain play for the screw to move or rock. The head of the screw 10 engages against the outer surface of the yoke member 7 and the shank of the screw is threaded into a threaded bore 12 80 of the rod member.

85 Preferably, there is a socket 13 in one side of the rod member communicating with the bore 12 and the pivot screw 10 is upset or riveted on its end as shown at 14 so that the 90 head will act as a stop against the shoulder 15 and prevent the screw from being entirely withdrawn from the rod member.

95 This screw is adapted to have a certain adjustment within the socket as will be referred to hereinafter. I have shown an aperture 16 through the opposite side of the yoke 100 through which a tool may be inserted for upsetting the head of the screw when the parts are first assembled.

Within the rod 8 which forms an extension of the yoke of the spoon member, I have provided a threaded socket 17 in which a stop screw 18 is threaded and there is a socket 19 to receive the head of the screw therein. This 105 screw may be adjusted for a purpose to be hereinafter described and when the iron is closed as shown in Figures 4 and 5 the enlargement 20 on the rod member 1 abuts against the head of the screw 18.

110 In Figures 6 to 12 I have shown the flange type of iron embodying the other features of my invention. In Figures 8 to 11 inclusive the iron consists in part of the spoon member 21 one edge 22 of which is thinned out and 115 slightly turned inwardly toward the axis of the spoon. The spoon member also has a yoke 23 corresponding with the yoke previously described and it also has a rod 24 forming a support for the handle 25. The rod member 120 26 which co-operates with the spoon member, has an enlargement 27 in which the pivotal screw 28 engages in the manner shown in Figures 6 and 7, and the rear end 29 of the rod is supplied with a handle member 30 125 in accordance with the first form of the invention.

130 In this form of iron the rod member is cut inwardly as shown at 31 to provide a shoulder 32 which is adapted to co-operate with

the narrow edge 22 of the spoon member for the purpose of pressing the hair against this edge and forming a fulcrum for the rod to rock on the flange 33 in order to throw the rod from the position shown in Figure 9 to the position shown in Figure 10.

This flange, in addition to performing the fulcrum feature referred to, serves the same purpose as the flange illustrated in my said 10 patent.

In Figure 12 I have shown the same type of rod as is shown in Figures 9 and 10 except that an electric heater 34 is inserted in a bore 35 extending lengthwise in the rod member. This is merely to indicate that the rod member may be heated by an electric unit; or, in the form shown in Figures 8, 9 and 10 the iron may be heated over a gas flame. The electric heating unit may be applied to the form of iron shown in Figures 1 to 5 inclusive if desired.

Operation

The operator may first adjust the iron to 25 have the hair gripped tightest either near the point of the iron or near the pivot. As shown in Figure 4 the stop screw 17 may be screwed upwardly in the socket 18 so that the member 20 rises a greater distance before striking against the stop screw when the iron is closed. When the stop screw is adjusted, as shown in this figure, the rod and spoon will not lie perfectly parallel when in closed position but they will diverge slightly, the angle being somewhat exaggerated 35 in Figure 4. This will cause the rod and spoon members to touch at their outer or free ends and to be spaced a gradually increasing distance toward the pivotal point 40 of the iron.

In this adjustment of the iron, if a lock of hair is placed between the rod and spoon members near their outer or free ends, the hair will be gripped tightly by these members; but if a lock of hair is placed nearer the pivotal point it will not be gripped as tightly as when placed near the free ends of the rod and spoon members.

If the stop screw 17 is turned down to the 50 position shown in Figure 5 it will arrest the upward movement of the member 20 in a different position when the iron is closed and as a result the rod and spoon members will diverge in a reverse order to that shown in 55 Figure 4; that is to say, when the iron is closed the rod and spoon members will be closer together near the pivotal point and be slightly separated near their outer or free ends. In this adjustment of the parts, if 60 the lock of hair is placed between the rod and spoon members at a point nearer the pivot the hair will be gripped tightly when these members are closed, but if the lock of hair is placed between the rod and spoon 65 members adjacent their outer or free ends

this member will not grip the hair as tightly as in the first position.

It will be apparent from this that the operator may adjust the screw 17 to obtain the condition best suited to the operator's style of work, so that any adjustment may be made to suit the taste or style of the operator. It will be apparent that at some intermediate point of adjustment of the screw the rod and spoon members will lie parallel 70 when in closed position if that is desired.

The pivot screw 10 may be turned in either direction. If it is turned in one direction the rod member 1 will be shifted laterally in relation to the spoon member, as shown 80 in Figure 7, for instance, so that the rod member will lie closest to one side of the spoon, i.e., the bottom side as viewed in Figure 2; and the spacing between the rod and the opposite side of the spoon will be greater, 85 as shown in Figure 7.

If the screw is turned in the opposite direction the rod member will be shifted upwardly as shown in Figure 6 so that the rod will not lie as close to the bottom edge of 90 the spoon as viewed in Figure 2 and will naturally lie closer to the top edge as viewed in this figure. The adjustment will be made in accordance with the amount of pinching action which the rod is to make against the 95 lower edge of the spoon in Figure 2. This adjustment having been made, it will not be necessary to alter the adjustment except when a change of action in the iron is desired.

When using the iron shown in Figures 1 to 5 the operator will grasp the handles in one hand, manipulating the lock of hair in the other, and will first open the iron to the dotted line position in Figure 1. The lock 105 of hair is then passed between the rod and spoon members at any desired point along their length and the handles are then pressed toward each other. As the rod and spoon members move toward each other they pivot 110 on the screw 10 which forms a fulcrum only on one side of the rod member so that there is both a pivotal and a rocking action as between the rod and spoon members. This will cause the rod member to press against 115 the edge 22 of the spoon member as the rod moves downwardly into the spoon; and when the final pressure is applied the member 20 will strike against the stop screw 17 which will then become a second fulcrum point so that further pressure of the handles toward 120 each other will cause the rod member to rock or tilt toward the upper edge 37 the action being illustrated in Figure 13. This causes 125 the hair to be drawn into and stretched between the rod and spoon and to tighten the hair around the edge 22 of the spoon.

As pointed out above, the adjustment of the screw 17 will vary the angle between 130 the rod and spoon members so that the grip-

ping action on the hair may be greatest near the point or near the pivot or it may be equal throughout their length. It will be understood that the lock of hair which is placed between the rod and spoon members offers some resistance to the closing of the rod in the spoon and to some extent forms a fulcrum for these members.

The single or one sided pivot constituting the screw 10 causes the rod member to press closely against the edge 22 of the spoon during the closing operation and this pivot also permits the rod to tilt or rock within the spoon in the manner above described. These actions permit the operator to produce a more perfect and more permanent wave in the hair than was possible with irons as heretofore constructed. It has been described above how the rod member may be shifted laterally by adjusting the fulcrum screw 10 as shown in Figures 6 and 7, in order to vary the pressure of the rod in relation to the edge 22 of the spoon member.

The device shown in Figures 8 to 12 operates very similar to the first described device. As far as the pivotal action on the fulcrum screw 28 is concerned and as far as the stop screw 17 is concerned, the action corresponds with the first form. When the lock of hair is placed between the rod and spoon members in this form of the device and the handles are pressed toward each other, the rod member approaches the spoon member, pressing on the lock of hair which passes between them. As the rod member moves down, the flange 33 presses the hair against the slightly inturned edge 22 of the spoon member, securing a tight grip at this point which is necessary to form the desired wave, and also to apply heat to the hair around the edge 22.

As further pressure is applied to the handles, the rod member will rock from the position shown in Figure 9 to approximately that shown in Figure 10, the shoulder 43 acting as a fulcrum, so that the opposite side of the iron approaches the edge 37 of the flange drawing against the hair which remains tightly clamped between the shoulder 32 and the edge 22 of the spoon. As a result, when the rod and spoon members are tightly pressed, the lock of hair is tightly gripped between the rod and spoon members and is more or less placed under tension. This tension is necessary, in conjunction with the heat, to set the wave so that it will be retained by the hair over an appreciable length of time. This tension could not be obtained in any of the irons as heretofore constructed. With the present type of iron it is possible to wave the hair so that it will be preserved from one shampoo to another, whereas with most irons the wave will last only a short period, such as day or two. I am enabled to accomplish results with the present iron which are substantially equal to a permanent

wave insofar as it is only necessary to wave the hair each time it is shampooed. But instead of obtaining only a small kink in the hair I am enabled to produce a true marcel wave and of sufficient lasting quality to be preserved over the period of time referred to.

It will be apparent that the one sided pivot described herein may be used without the other features of my invention and the stop screw 17 may also be used independently but when the several features described herein are used in the same iron their combined effect results in an iron capable of performing work which could not be performed heretofore.

Having described my invention, what I claim is:

1. In a curling iron the combination of a spoon member and a rod member co-operating therewith to clamp hair between them and having handle sections for manipulating said spoon and rod members, and a single pivotal member only, connecting said spoon member and said rod member at one side only thereof, whereby said spoon and rod members may pivot in relation to each other and also rock on said single pivotal member for the purpose set forth.

2. In a curling iron the combination of a spoon member and a rod member co-operating therewith to clamp hair between them and having handle sections for manipulating said spoon and rod members, said spoon member having a yoke provided with an aperture, said rod member having a single pivotal member projecting at one side only thereof, and passing through said aperture in said yoke member to pivotally connect said spoon and rod members whereby they may pivot in relation to each other and also rock on said single pivotal member for the purpose set forth.

3. In a curling iron the combination of a spoon member and a rod member co-operating therewith to clamp hair between them and having handle sections for manipulating said spoon and rod members, said spoon member having a yoke straddling the rod member and provided with an aperture therein, a single pivotal member connected with said rod member at one side only thereof and extending through said aperture and having a head on the exterior thereof, said aperture being large enough to permit said pivotal member to rock therein whereby said spoon and rod members may pivot in relation to each other and also rock on said single pivotal member for the purpose set forth.

4. In a curling iron the combination of a spoon member and a rod member co-operating therewith to clamp hair between them and having handle sections for manipulating said spoon and rod members, a single pivotal member for pivotally connecting said spoon member and said rod member at one side only.

thereof whereby said spoon and rod members may pivot and rock on said single pivotal member, and means forming an adjustable abutment between said rod and spoon members and adapted to vary the angle between said spoon and rod members when the latter are closed in relation to each other.

5. In a curling iron the combination of a spoon member and a rod member co-operating therewith to clamp hair between them and having handle sections for manipulating said spoon and rod members, a single pivotal member for pivotally connecting said spoon and rod members at one side only thereof whereby said spoon and rod members may pivot and rock on said single pivotal member, and an adjustable stop screw to the rear of said pivotal connection adapted to form an adjustable fulcrum between said 20 spoon and rod members to vary the angle between said spoon and rod members when in closed position.

6. In a curling iron the combination of a spoon member and a rod member co-operating therewith to clamp hair between them and having handle sections for manipulating said spoon and rod members, a screw engaging said rod member at one side only thereof and passing through one side of said 30 spoon member said screw being adapted to swivel in said spoon member whereby said spoon and rod members may pivot in relation to each other and also rock on said pivot, said pivot screw being adapted to be adjusted to 35 vary the relative positions of said spoon and rod members in a lateral direction.

7. In a curling iron the combination of a spoon member and a rod member co-operating therewith to clamp hair between them and having handle sections for manipulating said spoon and rod members, said rod member having a laterally extending threaded bore communicating with an enlarged recess, a pivotal screw threaded in said bore and 45 having a head on one end lying in said recess and adapted to limit the travel of said screw in one direction, said spoon member having a yoke provided with an aperture through which said pivot screw extends and 50 in which said screw may swivel to form a pivotal connection at one side only between said spoon and rod members on which said rod member is adapted to rock and to pivot for the purpose set forth, said screw being 55 adapted to be adjusted to vary the relative lateral relation of said rod and spoon members.

8. In a curling iron the combination of a spoon member and a rod member co-operating therewith to clamp hair between them and having handle sections for manipulating said spoon and rod members, a member for pivotally connecting said spoon and rod members at one side only thereof said connecting 65 member being adapted to swivel in said spoon

member whereby said spoon and rod members may pivot in relation to each other and rock on said pivot, said rod member having a longitudinal flange adapted to co-operate with one side edge of said spoon member to clamp the hair against the same.

9. In a curling iron the combination of a spoon member and a rod member co-operating therewith to clamp hair between them and having handle sections for manipulating said spoon and rod members, a member for pivotally connecting said spoon and rod members at one side only thereof said connecting member being adapted to swivel in said spoon member whereby said spoon and rod members may pivot in relation to each other and rock on said pivot for the purpose set forth, said spoon member having a narrow edge at one side turned inwardly in relation to the angle of the interior of said spoon member, said rod member having a flange engaging said inturned edge of the spoon member adapted to clamp the hair against said edge.

Signed at the city, county and State of New York, the 14th day of February, 1931.
